[57]

ABSTRACT

An ice dispenser for automatically dispensing crushed ice fed from an ice bin to a delivery opening of the ice bin in response to actuation of a push-plate beneath the opening is described. Crushed ice is lifted from the ice bin by means of an ice-elevating mechanism in the form of an auger having an ice feeder disc at its lower end and a stationary auger tube within which the auger turns for elevating the ice. The auger and its feeder disc are driven at the bottom through a drive pin mechanism journaled in the bottom of the ice bin and releasably connectable with the drive pin mechanism to permit removal and disassembly of the ice-elevating mechanism for cleaning.

AUTOMATIC ICE DISPENSER

This is a continuation-in-part of applicants' application Ser. No. 862,587, filed Aug. 25, 1969, and now patent no. 3,608,786, titled ICE DISPENSER, and is directed to a modified form of ice dispenser therein disclosed.

The present invention has for a principal object the provision of an automatic ice dispenser which will be particularly well suited to dispensing crushed ice of the type that is continuously manufactured, upon demand, by ice-making equipment wherein ice similar to crushed ice is delivered through a flexible conduit. As such, and in combination with an automatic-feed crushed ice machine, the ice bin of the ice dispenser comprising the present invention will be kept sufficiently full at all times to deliver normal requirements of dispensed ice. It is to be noted, however, that the ice dispenser ice bin can also readily be refilled manually, if required or desired.

It is an important object of the invention to provide an improved automatic ice dispenser of the above nature which will be comparatively simple in structure and operation, and wherein the parts and the surface areas coming into contact with the contained ice during use of the device are, for the most part, removable and smooth-surfaced for easy cleaning, sanitizing and sterilization where necessary. This is of special importance in hospitals and the like institutions where special care must be taken to eliminate all possible sources of bacteriological infection.

Still another object of the invention is to provide an ice dispenser of the character described which will be fully automatic in dispensing pre-determined portions of ice into a glass, pitcher or the like container without the necessity of touching the ice or machine by hand, thereby keeping the ice in as pure a condition as when supplied to the ice bin.

Another object of the invention is to provide an automatic, portion-controllable ice dispenser of the character described which comprises an insulated ice bin, ice-elevating mechanism in the form of an auger having a bottom ice-feeder disc, and an auger tube within which the auger turns for elevating the ice to a dispensing spout, and including electric drive mechanism extending through the bottom of the ice bin and being removably connectable to the unitary auger and ice-feeder disc for easy disassembly of the elevating mechanism.

Still another object is to provide an ice dispensing device which will be simple in construction, compact, readily portable and attractive in appearance, economical in cost, and dependable, efficient and durable in operation.

Other objects, features and advantages of the invention will be apparent from the following description when read with reference to the accompanying drawings. In the drawings, wherein like reference numerals denote corresponding parts throughout the several views:

FIG. 1 illustrates, in oblique view as seen from the front, an ice dispenser embodying the invention;

FIG. 2 is a rear elevational view of the ice dispenser, with a portion of the back panel broken away to illustrate interior constructional details;

FIG. 3 is a bottom view thereof;

FIG. 4 is a vertical cross-sectional view taken along the line 4-4 of FIG. 2 in the direction of the arrows and on an enlarged scale;

FIG. 5 is a horizontal cross-sectional view taken along the line 5-5 of FIG. 4 in the direction of the arrows;

FIG. 6 is a horizontal cross-sectional view taken along the line 6-6 of FIG. 4 in the direction of the arrows;

FIG. 7 is a horizontal cross-sectional view taken along the line 7-7 of FIG. 4 in the direction of the arrows;

FIG. 8 is a transverse cross-sectional view of the auger lift assembly illustrating the mechanism by means of which the lift tube is removably secured to the ice bin housing;

FIG. 9 is a vertical cross-sectional view taken along the line 9-9 of FIG. 7 in the direction of the arrows and illustrating the mechanism by means of which the cover assembly for the upstanding dispensing mechanism support structure is removably secured in place;

FIG. 10 illustrates, in oblique view as seen from the rear, the manually-controlled dispensing switch lever mechanism, shown separately; and

FIG. 11 is an exploded view of the ice dispenser illustrating how the auger lift assembly, cover members and overflow drain pan are removable for cleaning.

Referring now in detail to the drawings, numeral 10 in FIGS. 1, 2 and 11 designates an improved ice dispenser embodying the invention, the same being comprised, generally, of a substantially rectangular ice bin housing 11 having an upstanding dispensing mechanism support structure 12, an auger lift assembly 13 and an electric drive motor 14 supported in said ice bin housing near the lower end thereof and adapted to rotatively drive said auger lift assembly for elevating and dispensing ice in an interior ice chamber as is hereinbelow more particularly described.

The ice bin housing 11 is substantially rectangular in shape, having a bottom framework comprising opposed side angle-iron framework members 15, 16 (see FIGS. 3 and 5) interjoined, as by welding, with the front angle-iron framework member 17 and a back angle-iron framework member 18. As best illustrated in FIG. 3, the four corners of the bottom framework have welded or otherwise affixed thereto horizontally-disposed, triangular gusset plates 19 carrying downwardly-extending, screw-threaded, adjustable legs 20. Each of the leg supporting gusset plates 19 has secured along its outside edges a downwardly-extending leg shield 21 serving to hide the screw mechanism by means of which the legs 20 are adjustable (see FIG. 4). As illustrated in FIG. 3, a bottom cover plate 22, the corners of which are cut away adjacent the corner legs, is secured against the underside of the bottom framework structure.

The ice bin bottom framework comprising angle-iron members 15, 16, 17 and 18 has secured to the corners thereof, as by welding, front upstanding angle-iron members 23, 23 and rear upstanding angle-iron members 24, 24, the upper ends of which are similarly joined with an upper rectangular angle-iron structure 25 (partially illustrated in FIG. 4). The ice bin housing framework structure is covered in front by a fixed

cover plate 26 and at the sides by fixed side cover plates 27 and 28. A removable rear cover plate 29 is detachably secured in place as is hereinafter described. The front cover plate 26 and side cover plates 27 and 28 are secured in assembled relation by an integral corner trim assemblage 30 having downwardly-extending rectangular corner cover members 31, 32, 33 and 34 adapted to overlie vertical marginal portions of said front and side cover plates to retain them in place. The lower ends of said corner cover members when fitted in place extend somewhat downwardly below the underside of the above-described ice bin housing framework, whereat they are bent inwardly to secure the assemblage together. The corner trim assemblage 30 at its upper end comprises a top cover plate portion 35 having a circular ice chamber opening 36.

As illustrated in FIGS. 2 and 5, the upstanding rear angle-iron members 24, 24 have welded thereto near their upper ends opposed, inwardly-extending lugs 37, 38 drilled and tapped to receive attachment screws 39, 39 for removably securing the rear cover plate 29 in place. Additional screws 39 similarly secure the lower end of the rear cover panel 29 in place.

As best illustrated in FIG. 5, as means for supporting the auger lift assembly 13 and its associated ice chamber as hereinafter more particularly described, a pair of angle-iron support members 40, 41 extend diagonally from the zone of juncture of the side angle-iron framework member 16 and rear angle-iron framework member 18 to the zone of juncture of the front angle-iron framework member 17 and the side angle-iron framework member 15, said angle-iron support members being convergently arranged from back to front. Seated upon the angle-iron support members 40, 41 within the ice bin housing 11 is a cylindrical ice chamber 42 having a cylindrical sheet metal outer wall 43 and a concentrically-spaced cylindrical inner wall 44. The lower end of the cylindrical inner wall 44 extends somewhat short of the lower end of the cylindrical outer wall 43 and is formed thereat with an inwardly-offset peripheral lower end portion 45 (see FIG. 4). A shallow, cylindrical bottom cup member 46, the upper end of which is circumjacent the outside of the inwardly-offset lower end portion 45 of the inner wall 44 and is welded or otherwise secured thereto, provides the bottom interior wall of the cylindrical ice chamber 42. The bottom cup member 46 is fabricated with a substantially cylindrical, central bearing chamber 47 journalling a through axial pin 48 the lower end of which carries a drive sprocket 49. The upper or inner end of the axial pin 48 carries a circular bearing plate 50 having a centrally located indexing pin 51 and diametrically opposed index lugs 52, 53.

Means including the electric drive motor 14 is provided for driving the auger lift assembly 13 through the bearing plate 50, as is hereinafter more particularly described. To this end, as illustrated in FIG. 2, an intermediate upstanding angle-iron member 54 is provided between the upstanding rear angle-iron members 24, 24, for the securing of the motor 14 between said intermediate upstanding member and the adjacent corner of the ice bin housing framework as by bolts 55, 55. The drive shaft of the motor 14 extends downwardly, as best illustrated in FIG. 4, and carries a sprocket gear 56 mechanically interconnected with the sprocket 49 by a sprocket chain 57.

The annular space between the outer and inner walls 43, 44 of the cylindrical ice chamber 42 is filled with insulation 58; and the upper end of said inner wall is reversely bent to provide a smooth upper end or rim portion 59 extending through the circular opening 36 in the upper or top cover plate portion 35.

Referring to FIGS. 4 and 11, a U-shaped mounting plate 60 is secured interiorly between the intermediate upstanding angle-iron member 54 and its associated adjacent upstanding rear angle-iron member 24, which serves to mount an electric timer 61 controlling the drive motor 14 to dispense pre-determined portions of ice, as is hereinafter more particularly described.

Referring now to FIGS. 1, 2 and 4 of the drawings, it will be seen that the upstanding support structure 12 is of bent sheet metal and comprises a front face portions 62, rearwardly-extending side face portions 63, 64 and narrow, opposed, inwardly-extending rear portions 65 and 66. As best illustrated in FIGS. 6 and 11, the inside of the front face portion 62, near the upper end thereof, has welded thereagainst a pair of horizontally-extending, symmetrically-opposed top auger tube mounting brackets 67, 68. An integral auger tube central mounting bracket 69 is similarly secured against the inside of the front face 62 near the lower end thereof. The top and center auger tube mounting brackets 67, 68 and 69 serve to removably support an auger tube 70 comprising the auger lift assembly 13, as is hereinbelow more particularly described.

Referring to FIGS. 4 and 6, it will be seen that the upper end of the auger tube 70 is cylindrical in shape and has secured therein, as by bolts 71, a shallow bearing support cup 72 carrying a central bearing 73. Welded or otherwise secured about the auger tube 70 near the upper end thereof is a top auger tube and bearing support plate 74. As best illustrated in FIG. 8, the auger tube 70, at a point beginning somewhat below the bearing support cup 72, is deformed from circular or tubular cross-sectional configuration to provide diametrically-opposed, vertically-extending, radially-directed, side wall offset portions 75 and 76 extending to the lower end of said auger. The vertical side wall portions 75, 76 merge into offset, opposed, semi-cylindrical wall portions 77 and 78. As illustrated in FIGS. 7, 8 and 11, a bottom auger tube bracket 79 is welded or otherwise affixed against the outer wall of the auger tube 70 at a distance from the top auger tube and bearing support plate 75 equal to the distance between the top auger tube mounting brackets 67, 68 and the center auger tube mounting bracket 79 of the upstanding support structure 12. The auger tube 70 has further affixed to the outside thereof near its lower end a wide fin 80 extending arcuately outwardly.

The auger lift assembly 13 further comprises a removable auger 81, which is preferably formed by twisting an elongated plate of stainless steel. The upper end of the auger 81 has welded thereto at the upper end a concentrically-arranged, circular top plate 82 projecting centrally outwardly whereof is a journal pin 83. The journal pin 83 is diametrically cross-drilled, as indicated at 84, for the purpose hereinafter appearing. The lower end of the auger 81 has concentrically welded or otherwise affixed thereto a circular auger disc 85 integrally formed upon the upper surface of which is a pair of diametrically-opposed, upstanding, arcuate ribs 86 and 87. The arcuate ribs 86, 87 extend

spirally from the central zone of the auger disc 85. The auger disc 85 is also formed with an opposed pair of arcuate outer ribs 88, 89, said outer ribs being spaced at one end from their respective ribs 86 and 87 and extending along paths that are continual of the spiral paths defined by said respective ribs. The related ribs 86 and 88, in addition, have associated therewith a spaced continuum outer end rib 90, the outer end of which merges with the outer periphery of the auger disc 85 (see FIG. 5). As illustrated in FIGS. 4 and 5, the ribs 88, 89 and 90 have integrally formed therealong spaced, upstanding projections or nibs 91.

The over-all diameter of the circular auger disc 85 is slightly less than the inner diameter of the inner wall 44 of the cylindrical ice chamber 42 near the lower end thereof, to permit removable insertion in place of the auger lift assembly 13 as is hereinafter more particularly described. As best illustrated in FIG. 4, the peripheral marginal portion of the auger disc 85 is turned upwardly slightly as indicated at 92. The underside of the auger disc 85 is provided with a central recess 93 and a pair of symmetrically-arranged, diametrically-opposed recesses 94, 95 for indexing with the diametrically-opposed index lugs 52, 53 of the bearing plate 50 upon locating in place the auger lift assembly 13, as hereinafter described.

As illustrated in FIGS. 4 and 6, the removable auger is fitted in place within the auger tube 70 with its journal pin 83 extending through the upper end bearing 73 whereat it is removably secured in place for relative rotary motion with respect to said auger tube by means of a lock pin 96 inserted through the cross-drilled opening 84. As illustrated in FIG. 4, when so assembled the lower end of the auger tube 70 extends somewhat short of the opposed arcuate ribs 86, 87 to provide an entrance zone for the crushed ice to be lifted. As further illustrated in FIG. 4, the arcuate fin 80 and a rectangular flat push-plate 97 extending substantially tangentially from the other side of the auger tube 70, both extend down slightly beyond the lower end of said auger tube to terminate just short of the nibs 91 of the outer ribs 77, 78 and 79, and the opposed arcuate ribs 86, 87, respectively. As illustrated in FIGS. 4, 6 and 7, the auger lift assembly 13 is removably assembled with respect to the ice bin housing 11 by seating the top auger tube and bearing support plate 74 and bottom auger tube bracket 79, respectively, on the top pair of auger tube mounting brackets 67, 68, and the auger tube center mounting bracket 69 of the upstanding support structure 12, and securing it in place thereat with wing nut bolt assemblies 98.

Means is provided for discharging crushed ice by the auger lift assembly 13 through the front of the upstanding support structure 12. To this end, the upper end of the auger tube 70 is formed with a forwardly-facing, substantially rectangular opening 99, the lower arcuate edge of which is provided with a forwardly-extending, somewhat downwardly inclined ramp 100 and the sides of which are enclosed by forwardly-extending, opposed, parallel side walls 101, 102. The top of the forwardly-extending ice discharge opening thus defined is enclosed by a forwardly-extending, substantially rectangular portion 103 of the top auger tube and bearing support plate 74 (see FIG. 6). The forward end of the ice discharge opening above described fits in re-

5 gister with a like-sized opening 104 in the front face 62 of the upstanding support structure 12 to provide for discharge of ice to the front of the dispenser. The outer vertical sides of the front opening 104 are flanked by 10 outwardly-extending side enclosure walls 105, 106 swingably journaled between which and the upper end portions thereof is a liftable outer end cover plate 107 having in-turned marginal edge portions 108, 109, receivable in overlying relation with respect to outer edge portions of said side enclosure walls.

15 Electrical switch means is provided for energizing the electric drive motor 14 for dispensing ice automatically whenever a glass or other container is moved in position under the dispensing opening 104. To this end, an arcuate push-plate 110 is arranged at the front of the front face 62 of the upstanding support structure 12 under the above-described cover structure of the dispensing opening 104, (see FIGS. 4, 7 and 10) said push-plate being supported at the outer end of a U-shaped actuating bar 111, the central portion of which is swingably journaled with respect to a pair of horizontally-spaced brackets 112, 113 fixed against the 20 inside of the front face 62, and the inner end of which terminates in abutment with the actuating arm 114 of a microswitch 115 fixed against the inside face 63 of the upstanding support structure 12. The arrangement is such that when the push-plate 110 is pushed inwardly, such as by use of a glass or other container, the inner end of the U-shaped actuating bar 111 will actuate the 25 microswitch 115. It will be understood that the microswitch 115 will be connected in an energizing circuit for the drive motor 14 to rotate the auger 81 (clockwise as viewed in FIG. 5) through mechanical interconnection with the bearing plate 50, as described above, to elevate the crushed ice within the ice chamber 42 for discharge through the front opening 104. The motor energizing circuitry may also include the electric timer 21 for the purpose of controlling or 30 predetermining the quantity or portion of ice to be dispensed each time the push-plate 110 is actuated.

35 The upstanding mechanism support structure 12 further comprises a removable top cover member 116 having a forwardly-extending, overhanging top wall 117, and downwardly-extending front, rear, right side and side flanges 118, 119, 120 and 121, respectively. The top cover member 116 also comprises a side-to-side back plate 122 extending downwardly of the top wall 117 at the rear thereof, which serves to cover the rear opening of the support structure 12 when fitted in place. The lower end of the back plate 122 is inwardly offset, as indicated at 123 in FIG. 11, for the purpose 40 hereinafter appearing; and said back plate is formed along each side with opposed, inwardly-directed, parallel flange portions 125, 126 (see FIG. 6). As further illustrated in FIG. 6, the flange portions 125, 126, when the top cover member 116 is fitted into place, fits slidingly into place between opposed, parallel, inwardly-directed, vertical flange portions 127, 128, respectively, provided at side portions of the inwardly-extending rear portions 65, 66 of the upstanding 45 mechanism support structure 12.

50 As means for removably locking the top cover member in place, the lower ends of the flange portions 124, 125, thereof are provided with upwardly-extending notches 130, 131 adapted to hookingly engage over

opposedly-extending pins 128 and 129 fixed at lower end portions of the flange portions 127, 128 (see FIGS. 6, 9 and 11).

As illustrated in FIGS. 4 and 11, a two part lid is provided for the cylindrical ice chamber 42, comprising a thick-walled, semi-circular front lid portion 132, insulated as indicated at 133, and a semi-circular rear lid portion 134 insulated as at 134. The front lid 132, provided with a central opening for passage of the auger tube 70 when fitted in place as herein after described, is assembled by fitting at the rear of the open ice chamber 42 and then rotating it to front position. The rear lid portion of 134, also provided with a central opening for passage of the auger tube 70, is thereafter fitted in place. As illustrated in FIGS. 4 and 11, the rear lid portion is provided with a transverse, upwardly-extending cover plate 135, the upper end of which seats in the transverse recess defined by the inwardly off-set portion 133 of the back plate 122 comprising the dispensing mechanism support structure 12.

As best illustrated in FIGS. 1, 4 and 11, the ice bin housing structure 11 also comprises a drain housing extending along the front of the dispensing mechanism support structure 12 and at the base thereof, indicated generally at 137, said drain housing comprising upstanding wall 138, side walls 139, 140 and top wall 141. The top wall 141 is formed with an elongated, side-wardly-extending opening removably seated within which is a shallow drain pan 142, having peripheral top flanges 143. The drain pan 142 is formed with an inwardly-flanged bottom removably seated upon which is a perforated drain plate 144.

As illustrated in FIGS. 2, 4, 5, and 6, the forward portion 146 of the ice bin housing top cover portion 35, at the left-hand side thereof as seen from the front, is equipped with an upper drain fitting 145 joined with a flexible drain hose 149 leading to a T-drain fitting 148 connected to and communicating also with the bottom of the cylindrical ice chamber 42. The remaining outlet of the T-fitting 148 serve as a discharge opening for melted ice flowing from the ice chamber 144 and overflow ice water spilling into the drain pan 142.

In use, FIG. 11 illustrates how various above-described parts of the ice bin housing dispensing mechanism support structure 12, the auger lift assembly 16 and the drain pan 142 can readily be disassembled for cleaning. In operation, after assembly as described above, energization of the electric drive motor 14 turns the auger 81 and its associated auger disk 85 in the clock-wise direction, as seen in FIG. 5. The arcuate ribs 86 through 90 carry the contained crushed ice into the opposedly-curved, stationary arcuate fin 80 so that the ice is continuously pushed centrally to the auger tube 70. Referring to FIG. 4, it will be noted that the lower end of the auger tube 70 extends somewhat short of the upper surface of the auger disk 85 to provide an entrance for the passage of the ice upwardly through said tube. The opposed spiral ribs 86, 87 of the auger disk 85, upon turning of the auger in a clock-wise direction as above described, serve to propell the ice inwardly for engagement by the auger 81. The relatively fixed push-plate 97 serves to break up or loosen compacted ice masses, if they should occur, at the lower central zone of the ice chamber just prior to delivery to the auger tube 70 for lifting.

In its lifting movement within the auger tube 70, peripheral portions of the ice will come into abutting engagement with the opposed, interior, vertically-extending side wall portions 75, 76 of said auger tube, 5 which promotes substantially vertical sliding-lifting of most of the ice being elevated to the discharge ramp, while at the same time minimizing any tendency for the ice to jam, which would otherwise result in non-uniform dispensing.

When using the ice dispenser in association with an ice-making machine delivering crushed ice through a flexible tube of conduit, the delivery conduit could extend through appropriate side openings into the interior of the cylindrical ice chamber 42. A thermally-responsive switch (not illustrated herein), arranged to sense the temperature of the inner wall 44 of the ice chamber 42 at the zone of maximum height to which ice is to be supplied to said chamber, could be used for controlling the operation of the ice-making machine, thereby rendering the ice dispenser system fully automatic.

While I have illustrated and described herein a dispensing device for crushed ice, it is to be understood 25 that it could as well be adapted for use in dispensing demand portions of other granular, particulate, or fragmented materials. The invention, in brief, comprises all the modifications and embodiments coming within the scope and spirit of the following claims.

30 What we claim as new desire to secure by Letters Patent is:

1. A crushed ice dispenser comprising, in combination, an ice bin housing, a cylindrical ice bin affixed within said housing, rotative auger means for lifting ice from the interior of said ice bin for dispensing at a position above said ice bin housing, said auger means comprising an elongated auger and an auger tube within which said auger is rotatively journaled, in auger disk 35 concentrically affixed to the lower end of said auger for rotation in unison therewithin, a power drive unit, means releasably interconnecting said power drive unit with said auger disk and controlled by vertical movement of said auger in said ice bin for rotating said auger disk and said auger within said ice bin, at least a portion of the lower end of said auger tube extending somewhat short of the lower end of said auger to provide an entrance to said auger tube above said auger disk, and means for moving ice in said ice bin in the direction of 40 said entrance for elevation of ice within said tube by said auger, the upper end of said auger tube having a discharge opening for the dispensing of ice, said releasable means for said auger disk comprises a bearing concentrically arranged within the bottom of said ice bin, an axial drive pin journaled in said bearing and extending through said bin, a bearing plate carried by the inner end of said axial pin, and releasable interengagement means between said bearing plate and the underside of said auger disk.

60 2. An ice dispenser, as defined in claim 1 wherein said auger disk is of slightly lesser diameter than the interior diameter of said ice bin.

65 3. An ice dispenser, as defined in claim 1 wherein said power drive unit comprises a rotary electric motor secured within said housing and drivingly interconnected with the outwardly-extending end of the said axial drive pin for rotary said drive pin.

4. A ice dispenser as defined in claim 3 including a plurality of arcuate ribs formed in the upper surface of said auger disk and extending spirally outwardly of a central zone thereof for moving ice in said ice bin in the direction of the lower end of said auger tube.

5. An ice dispenser as defined in claim 4 including a plurality of upwardly-extending nibs spaced along and extending upwardly of said arcuate ribs.

6. An ice dispenser as defined in claim 1 wherein said auger is in the form of a twisted elongated plate, the upper end of said auger being removably journaled in the upper end of said auger tube, and means for releasably securing the upper end of said auger tube with respect to said ice bin housing at a position above said ice bin.

7. An ice dispenser as defined in claim 6 wherein said auger tube securing means comprises a dispensing

mechanism support structure affixed to and extending upwardly of said ice bin housing.

8. An ice dispenser as defined in claim 7 including a plurality of arcuate ribs formed in the upper surface and extending spirally outwardly of a central zone of said auger disc for moving ice in said ice bin in the direction of the lower end of said tube, and an arcuate fin secured at one end to said auger tube near the lower end thereof and being curved in the opposite direction to the directions of curvature of said arcuate ribs.

9. An ice dispenser as defined in claim 8 including a rectangular push plate affixed to and extending substantially tangentially outwardly of said auger tube near the lower end thereof in the direction of curvature of said arcuate fin and arranged substantially diametrically opposite with respect thereto.
